SELF TIGHTENING ELECTRICAL CONNECTER

Rob Roy MacDonald, Bayside, N. Y., assignor of
one-half to Leo O. Smith, Bayside, N. Y.

Application March 2, 1932, Serial No. 596,216

3 Claims. (Cl. 173—332)

The present invention relates to connectors for connecting electrical conduits together and embodies, more specifically, an improved form of electrical connector wherein the cooperating 5 connecting elements are effectively connected by a simple movement comprising the axial interengagement of the elements.

Various connectors have been provided wherein in the securing of the connecting elements there-10 is effected by means of suitable clamping means which are independently operated. The present invention seeks to provide a connector which is of such construction that an effective electrical connection is afforded by a simple con-15 necting operation without requiring an additional operation to adjust or manipulate a securing mechanism.

An object of the invention is to provide an electrical connector having cooperating terminals which are effectively secured in connected 20 position during the movement thereof into engagement with each other.

A further object of the invention is to pro-25 vide a connector of the above character wherein movement of the cooperating elements thereof into engagement causes an action which forces the elements intimately into contacting relationship.

A further object of the invention is to provide 30 a connector wherein male and female members are adapted to be secured together, additional means being provided for forcing the members into intimate engagement during the connecting operation.

A further object of the invention is to pro-35 vide a device of the above character wherein a male connecting member is provided with a circular skirt formed as an annular cam to engage the female member and force the prongs thereof into intimate engagement with the male member.

Further objects, not specifically enumerated 40 above, will be apparent as the invention is de-45 scribed in greater detail in connection with the accompanying drawing, wherein:

Figure 1 is a plan view, partly broken away, showing a connector constructed in accordance with the present invention.

Figure 2 is a view in end elevation, showing 50 the connector of Figure 1.

Figure 3 is a view in section, taken on line 3—3 of Figure 1, and looking in the direction of the arrows.

Figure 4 is a view in section, taken on line 4—4

of Figure 1, and looking in the direction of the arrows.

Referring to the above drawing, cooperating terminal blocks 10 and 11 are shown as being provided each with a plurality of connector elements. It will be understood, of course, that the specific number of connector elements carried by the blocks is of no consequence, any number from one to a plurality of connections being adapted for use in connection with the present invention. The ends of two pairs of wires are to be connected together, a connector formed with two sets of cooperating terminals being advantageously used and this particular form is illustrated in the above drawing. Terminal block 10 is thus formed with a recess 12 which is adapted to receive the ends of wires to be connected, and recesses 13 which are adapted to receive connector elements 14, described in detail hereinafter.

The skirt 15 is secured to each connector element 14 to facilitate the connection of the ends of the wires thereto. In order that the exposed parts of the terminals may be protected a cover plate 16 is provided, screws 17 serving to secure the cover plate to the block 10. If desired, the portion of the cover plate 16 which lies above the recess 12 may be formed with downwardly extending teeth 18 to engage the insulation of the wires and facilitate the securing thereof within 75 the block 10.

Each connector member 14 is formed with a shoulder 19 having an annular flange 20 projecting axially of the element 14. Concentric with the flange 20 is an outwardly tapering male contacting member 21, the inner surface of the flange 20 tapering or curving toward the axis of the element 14, as indicated at 22.

The terminal block 11 is provided with recesses 12 and 13, cover plate 16, and projecting teeth 95 18 in a manner similar to that described in connection with the terminal block 10. In order that one of the connector members may be completely protected, the block 11 with projecting flanges 23 which are adapted to receive female 100 contacting elements will now be described.

Block 11 is adapted to receive the desired number of connector elements 24, these elements being formed with extensions 25 to which sleeves 26 are secured by means of pins 27. Sleeves 26 are formed with female contacting members 28 which extend beyond the projection 25 and form recesses which are adapted to receive the male members 21. These members 28 are slotted as indicated at 29 and are formed with a tapered 110

internal surface 30 which causes the interior diameter of the member 28 to be smaller at the outer extremity thereof than adjacent the member 25.

5 As the male and female members are advanced into engagement, the ends of the female members are sprung outwardly by the male members and then, during continued axial movement, into engagement. The ends of the member 28 engage the interior surface of the flange 20. Further movement into engagement causes the ends of the members 28 to be cammed down into intimate engagement with the sides of the male members and thus form an effective electrical contact.

10 While the invention has been described with specific reference to the accompanying drawing, it is not to be limited, save as defined in the appended claims.

15 20 I claim as my invention:

1. A connector comprising terminal members having cooperating male and female elements, the male element being tapered outwardly to a point of maximum diameter and the female element being tapered inwardly to a point of max-

imum diameter, and an annular flange mounted with the male element, said flange having a tapering surface to engage the female element and direct the same radially against the male element.

2. A connector comprising terminal members having cooperating male and female elements, the male element being tapered outwardly to a point of maximum diameter and the female element being tapered inwardly to a point of maximum diameter, and an annular flange formed with a sloping cam face and mounted with the male element to engage the female element and direct the same radially against the male element.

3. A connector comprising terminal members having cooperating male and female elements, the male element being tapered outwardly to a point of maximum diameter and the female element being slotted and tapered inwardly to a point of maximum diameter, and an annular flange formed with a sloping cam face surrounding and sloping toward the male element to engage the female element and direct the same radially against the male element.
